(57) **CLAIM**

I claim the ornamental design for an office panel with dry erase surface, as shown and described.

DESCRIPTION

FIG. 1 is a front perspective view of an office panel with dry erase surface according to my new design.

FIG. 2 is a rear perspective view of the office panel with dry erase surface of FIG. 1.

FIG. 3 is a front elevation view of the office panel with dry erase surface of FIG. 1.

FIG. 4 is a rear elevation view of the office panel with dry erase surface of FIG. 1.

FIG. 5 is a right side elevation view of the office panel with dry erase surface of FIG. 1.

FIG. 6 is a left side elevation view of the office panel with dry erase surface of FIG. 1.

FIG. 7 is a top plan view of the office panel with dry erase surface of FIG. 1; and,

FIG. 8 is a bottom plan view of the office panel with dry erase surface of FIG. 1.

In the drawings, the broken lines depict portions of the office panel that form no part of the claimed design. The appearance of any portion of the article between the break lines forms no part of the claimed design such that the claimed design may be applied to office panels having different height:width aspect ratios as viewed from the front.
